Primary Examiner — Susan Bennett Hattan*Assistant Examiner* — Barbara B Lohr(74) *Attorney, Agent, or Firm* — Roddy M. Bullock; Betty J. Zea**CLAIM**

The ornamental design for a paper product, as shown and described.

DESCRIPTION

The sole FIGURE is a top plan view of a paper product showing my new ornamental design.

The broken lines in the figure form no part of the claimed design. The broken lines indicate that a specific length and width of the paper product forms no part of the claimed design and that the design may continue in one or more directions. The surfaces or portions not shown in the drawings or described in the specification form no part of the claimed design.
